JOHN H. LICKERT, OF EVANSTON, ILLINOIS, ASSIGNOR TO KIT-CHIN-KIT CORPORATION, OF EVANSTON, ILLINOIS, A CORPORATION OF ILLINOIS.

DESIGN FOR A COMBINATION KNIFE AND FORK.

57,683.

Specification for Design.

Patented Apr. 26, 1921.

Application filed March 5, 1920. Serial No. 363,574. Term of patent 14 years.

To all whom it may concern:

Be it known that I, JOHN H. LICKERT, a citizen of the United States, residing at Evanston, in the county of Cook and State of Illinois, have invented a new, original, and ornamental Design for a Combination Knife and Fork, of which the following is a specification, reference being had to the accompanying drawing, forming a part thereof.

The drawing shows a plan view and a side elevation view of a combination knife and fork, showing my new design.

I claim:

The ornamental design for a combination knife and fork, as shown.

JOHN H. LICKERT.
